METHOD AND APPARATUS FOR OPERATING REGENERATORS

Clarence J. Schilling, Allentown, Pa., assignor to Air Products Incorporated, a corporation of Michigan

Filed Feb. 3, 1956, Ser. No. 563,340

21 Claims. (Cl. 62—13)

This invention relates to low temperature separation of gaseous mixtures by liquefaction and fractionation and more particularly to fractionating cycles employing cold regenerators.

In low temperature separation of gaseous mixtures by liquefaction and fractionation cold regenerators have been employed to reduce the temperature of the stream of gaseous mixture by heat exchange with streams of cold product from the fractionating operation. In the separation of binary gaseous mixtures, two cold product streams are available for this purpose, such as oxygen and nitrogen cold products streams in the separation of air, for example. Generally a set of cold regenerators, including at least one pair of regenerators, is employed to establish the required heat exchange relationship between each cold product stream and separate component streams of gaseous mixture, the component streams and the capacity of the regenerators being proportioned in accordance with the mass of respective cold product streams. The regenerators of each set are provided with feed conduits controlled by periodically operated switching valves so that the cold products streams and respective component streams of the gaseous mixture are alternately passed in opposite directions through the regenerators. Cold regenerators usually comprise a vertically disposed hollow casing of cylindrical form having top and bottom closed ends to which the conduits are connected for conducting the fluid streams to and from the casing. The chamber defined by the casing is substantially filled with low-temperature heat regenerator packing in the form of a bed of relatively small particles such as stone or metal pellets. A screen device may be provided within the casing adjacent its lower end to prevent particles of packing from entering the conduit connected to the bottom end of the casing.

In the liquefaction and fractionation of gaseous mixtures, during one phase of operation, a stream of gaseous mixture under relatively high pressure enters the upper end of the first regenerator of a regenerator set, flows downwardly through the packing material and is conducted from the lower end of the first regenerator at a lower temperature, while a cold product stream, under relatively low pressure, enters the lower end of a second regenerator, flows upwardly through the packing material and is exhausted from the upper end of the second regenerator to a region of low pressure. During the next phase of operation, the regenerators of the set are switched so that the stream of gaseous mixture flows downwardly through the second regenerator and the cold product stream flows upwardly through the first regenerator. In particular, in the fractionation of air, streams of air entering the upper ends of the regenerators may be under a pressure of 80 pounds gage, while the nitrogen and oxygen cold products streams may enter the regenerators under a pressure of 4 pounds gage and may be exhausted from the upper ends of the regenerators at atmospheric pressure. Thus, when a cold regenerator passing a relatively high pressure stream of gaseous mix-

2

ture is switched to terminate the downward flow of the stream of gaseous mixture and initiate upward flow of a cold product stream, the regenerator contains a residual volume of gaseous mixture under relatively high pressure at the instant the switching operation takes place. When the switching operation is complete, the residual volume of relatively high pressure gaseous mixture flows at a high velocity upwardly through the packing material and outwardly from the upper end of the regenerator to a low pressure region, such as the atmosphere. This relatively high velocity flow continues until the residual volume of gaseous mixture is exhausted and the pressure of the regenerator chamber approaches the pressure of the cold product stream. Although the pellets comprising the packing material possess appreciable density, the high velocity, upward flow of the residual gaseous mixture moves the packing material upwardly and causes the production of powder or fines due to attrition or crushing of the pellets. It has been the prior practice to install a grid supported screen within the casing adjacent the upper surface of the packing material to prevent upward movement of the pellets. In view of the magnitude of the upward forces involved a relatively heavy grid structure is required, and since the materials forming the casing and the packing material possess different coefficients of expansion, it is necessary to spring load the grid structure to compensate for temperature fluctuations of the casing. Due to the repeated expansion and contraction of the casing, the upward force applied onto the packing material, due to the high velocity flow of the residual high pressure stream of gaseous mixture, results in production of fines by attrition or crushing of the pellets even when a grid structure is employed. It is necessary to remove the fines from the cycle by a filtering process to prevent their entry into components of the cycle such as expansion devices, for example. The filtering devices present an increasing pressure drop in the conduits feeding the regenerators as fines accumulate in the filters which due to plugging disadvantageously affects operation of the cycle. Also, the filters require periodic inspection and cleaning.

It is an object of the present invention to provide a novel method of and apparatus for fractionating gaseous mixtures which overcome the foregoing problems.

Another object is to provide a novel method of and apparatus for fractionating gaseous mixtures which eliminate problems attendant the use of switching regenerators including packing material in the form of pellets.

Another object is to provide a novel method of and apparatus for fractionating gaseous mixtures by which the production of fines from regenerator packing material is prevented.

Still another object of the present invention is to provide a novel fractionating operation employing cold regenerators including packing material in the form of pellets in which the upward flow of fluid streams through the regenerators is controlled in such a manner as to prevent attrition of the pellets and resulting production of fines.

A still further object of the present invention is to provide a novel flow control device particularly adapted for use with cold regenerators in a fractionating operation by which the flow of fluid streams through the regenerators is maintained below a critical velocity irrespective of the pressures involved.

A still further object is to provide a novel device for maintaining a fluid stream of constant flow independently of pressure variation.

Other objects and features of the present invention will appear more fully below from the following detailed description considered in connection with the accompanying drawings. It is to be expressly understood, however,

that the drawings are designed for purposes of illustration only and not as a definition of the limits of the invention, reference for the latter purpose being had to the appended claims.

In the drawings, in which similar reference characters denote similar elements throughout the several views:

Fig. 1 is a diagrammatic presentation of a low temperature fractionating cycle embodying the principles of the present invention;

Fig. 2 is an elevational view, partially in section, of a flow control device provided by the present invention, the control device being shown in open position and in operative relationship with a cold regenerator;

Fig. 3 is a view in vertical section of the control device of Fig. 2, the control device being shown in closed position;

Fig. 4 is a view in section taken along the line 4—4 of Fig. 2, and

Fig. 5 is an elevational view, in section, of a flow control device constructed in accordance with another embodiment of the present invention.

The present invention provides a novel method of and apparatus for controlling the flow of relatively high pressure residual gas upwardly from regenerators in such a manner as to prevent the production of fines from the particles or pellets comprising the packing material of the regenerators. According to the present invention the velocity of the fluid stream flowing upwardly through a regenerator is maintained below a critical velocity, irrespective of the pressure involved, such that the resulting upward force on the packing material is at all times less than the density of the packing material. Thus a quiescent bed of packing material is obtained and the use of spring loaded screens for preventing movement of the packing material is rendered unnecessary.

With reference more particularly to Fig. 1 of the drawings, there is disclosed an air fractionating cycle which incorporates the principles of the present invention. Although the present invention is disclosed and described in the environment of separating air into low boiling point nitrogen and oxygen components, it is to be expressly understood that the principles of the present invention are applicable to the separation of other gaseous mixtures not limited to binary mixtures. As shown, the fractionating cycle includes a two stage column 10 having a high pressure section 11, a low pressure 12 and a conventional refluxing condenser 13. The cycle also includes two sets of cold regenerators 14 and 15, each comprising one pair of cold regenerators 15, 16 and 17, 18, respectively. It is to be expressly understood however, that additional sets may be provided and that each set may include more than two regenerators. A stream of gaseous mixture under relatively high pressure, such as air at 80 pounds gage, for example, enters the cycle through a conduit 20 serially connected by a proportioning valve 21 to a conduit 22. Branch conduits 23 and 24 are connected to the conduit 20 and to oppositely related individual ports 25 and 26 of a pair of two positioned switching valves 27 and 28, respectively, the other individual ports 29 and 30 being joined by a conduit 31 communicating with the atmosphere through a conduit 32. The switching valves include common ports 33 and 34 connected to conduits 35 and 36 communicating with the upper ends of the cold regenerators 16 and 17, respectively. Conduits 37 and 38 respectively extending from the bottom ends of the regenerators 16 and 17 are connected to common ports of switching valves 39 and 40. One pair of oppositely disposed individual ports of the switching valves 39 and 40 are connected to a common conduit 41 by way of conduits 42 and 43, while the other pair of individual ports are joined by a common conduit 44. The upper ends of the regenerators 18 and 19 of the set 15 are connected to the conduit 22 and to a conduit 45 leading to the atmosphere in a similar manner by means of switching valves 46 and 47, one pair of

opposed individual ports being connected to the conduit 22 by way of conduits 48 and 49 and the other pair of individual ports being joined together by a conduit 50 communicating with the conduit 45. The common ports of the switching valves 46 and 47 communicate through conduits 51 and 52 to the upper ends of the regenerators 18 and 19, respectively. Also, the lower ends of the regenerators 18 and 19 are connected through conduits 53 and 54 to the common ports of a pair of switching valves 55 and 56, the latter switching valves having one pair of opposed individual ports connected to the conduit 41 by way of conduits 57 and 58, and another pair of individual ports connected together by a common conduit 59.

With the switching valves in the positions shown in the drawing, a major component stream of the incoming air flows downwardly through the regenerator 16 while the remaining minor component stream flows downwardly through the regenerator 18, the proportions of the total air stream comprising component streams being determined by the valve 21. The component air streams are cooled upon flowing downwardly in the regenerators 16 and 18 which have been previously cooled in a manner described below, and leave the lower ends of the regenerators by way of conduits 37 and 53 at a relatively low temperature, such as approximately the dew point temperature corresponding to the existing pressure. The cold streams pass through conduits 42 and 57 and are merged in the conduit 41, and the merged streams are conducted to an expansion valve 61 and then introduced by way of a conduit 62 into the high pressure section 11 of the fractionating column 10. The high pressure section 11 includes a plurality of fractionating trays 63 provided with liquid vapor contacting devices 64 of the bubble cap type, for example, and the gaseous mixture undergoes preliminary fractionation therein producing liquid crude oxygen fraction collecting in a pool 65 in the base of the high pressure section and gaseous nitrogen fraction which flows upwardly into the refluxing condenser 13 where it is condensed by heat exchange with liquid oxygen product collecting in a pool 66 in the base of the low pressure section 12. The liquefied high pressure nitrogen fraction flows downwardly from the refluxing condenser with a portion of the liquid providing reflux for the high pressure section 11, and another portion collecting in a pool 67 formed by a trough 68. A stream of liquefied nitrogen fraction is withdrawn from the pool 67 through a conduit 69, passed through an expansion valve 70 and introduced into the upper end of the low pressure section as reflux liquid. The feed for the low pressure section comprises a stream of liquid crude oxygen fraction withdrawn from the pool 65 by way of a conduit 71, expanded in an expansion valve 72 and introduced into the low pressure section at a mid point 73. The low pressure section 12 includes a plurality of fractionating trays 75 each provided with liquid vapor contact devices 76, and the fractionating process is completed therein producing a substantially pure liquid oxygen product collecting in the pool 66, and a gaseous nitrogen product which flows upwardly in the dome of the low pressure section and leaves the section through a conduit 77. The conduit 77 is joined to the common conduit 44 connected between the switching valves 39 and 40. With the switching valves in the position shown, the stream of cold nitrogen product gas passes through the cold regenerator 17 and is exhausted from the cycle at substantially atmospheric temperature and pressure through the conduit 32. The oxygen product may be withdrawn from the column 10 in liquid phase, or in gaseous phase through a conduit 78 communicating within the low pressure section above the pool of liquid oxygen product 66. The conduit 78 is joined to the common conduit 59 connected to the switching valves 55 and 56, and with the switching valves in the position shown in the drawing, the stream of gaseous oxygen

product flows upwardly through the regenerator 19 and leaves the cycle through the conduit 45 at substantially atmospheric temperature and pressure.

The regenerators 16, 17, 18 and 19 are of similar conventional construction, and although the regenerators of the sets 14 and 15 are of different capacity, it will only be necessary to describe in detail the construction of one regenerator, such as the regenerator 16. As shown in Fig. 2, the regenerator 16 comprises a hollow cylindrical casing 80 closed at its upper and lower ends by dished end plates 81 and 82, respectively, defining a chamber 83 substantially completely housing a bed 84 of low temperature heat regenerator packing material in the form of a plurality of relatively small particles or pellets 85 of heat storing material such as stone, quartz or metal. The lower end 82 of the regenerator is provided with a centrally disposed opening 86 communicating with the conduit 37, and a screen 87 is positioned within the chamber 83 overlying the opening 86 to prevent the pellets from flowing out of the chamber 83 into the conduit 37. In this type of regenerator the flow of cold product streams upwardly through the packing material cools the particles of heat storing material, and when the switching valves are operated to pass the incoming air stream downwardly through the packing material the stored cold is transferred to and cools the air stream.

As mentioned above, the incoming air stream in the conduit 20 is under relatively high pressure, such as 80 pounds gage, while the cold product nitrogen and oxygen streams enter the lower ends of the regenerators at a relatively low pressure, 4 pounds gage for example. Thus, when the switching valves are moved from one phase of operation to the other, the regenerators previously passing a stream on incoming air will contain a residual volume of air under the relatively high pressure which must be exhausted from the upper ends of the regenerators before respective cold product streams may flow therethrough. According to the present invention the velocity of the residual air flowing outwardly from the top of the regenerators is controlled to allow the residual air to exhaust as quickly as possible from the regenerators without producing disturbing effects upon the bed 84 of packing material. This is accomplished by means of a novel flow control valve 90 positioned at the upper ends of the regenerators in communication between the interior of the regenerators and their respective feed conduits 35, 36, 51 and 52. The flow control valves 90 function to maintain the rate of flow of fluid streams upwardly through the regenerators at all times slightly below a critical value above which the resulting upward force on the packing material 84 would exceed the density of the packing material, irrespective of the pressure drop of the residual air during the exhausting process. The flow control valves also function to allow normal rates of flow of the cold product streams upwardly through the regenerators and the streams of gaseous mixture downwardly through the regenerators.

As shown more particularly in Figs. 2, 3 and 4 of the drawings, each of flow control valve 90 comprises a vertically disposed hollow cylindrical member 91 having its lower end 92 extending through an opening in the top end plate 81 of the regenerator in communication with the regenerator chamber 83 and secured thereto by any suitable means, such as by welding, for example, and an upper end 93 provided with an annular flange 94 for forming a connection with one of the feed conduits 35, 36, 51 or 52. The flow control valve further includes a movable member 95 comprising an elongated valve stem 96 having a piston 97 secured to its upper end and a valve member 98 secured to its lower end; the valve member 98 including a horizontally disposed circular plate member 99 and an upstanding hollow cylindrical member 100 secured at its lower end to the plate member 99 in concentric relation with the valve stem and having a plurality of openings 101 extending up-

wardly from its other end, the area of the openings gradually decreasing in a direction toward the plate 99 and terminating in a plane spaced upwardly from the lower end of the cylindrical member 100 to provide a continuous portion 102 at its lower end adjacent the plate 99. The piston 97 is mounted for axial movement in a closed cylinder 103 rigidly supported in concentric relation within the casing 91 by means of radial vanes 104, the cylinder and the piston defining a chamber 105. An annular flange member 106 is positioned within the casing below the cylinder 103, and is provided with a centrally disposed opening 107 for receiving the hollow cylindrical member 100. The movable member 95 is supported in its lowermost position in the casing 91, as shown in Fig. 2, by means of a plurality of angularly spaced stop members 108 located in a horizontal plane below the flange member 106 and projecting inwardly from the casing to beyond the outer periphery of the plate member 99. The plate member 99 extends outwardly beyond the walls of the hollow cylindrical member 100 and presents an annular flange 109 for contacting the lower annular surface 110 of the flange member 106 to limit upward movement of the movable member 95 to the position shown in Fig. 3. The longitudinal space between the planes of the annular flange member 106 and the stop members 108 and the length of the hollow cylindrical member 100 are proportioned to preferably maintain contiguous relationship between the outer surface of the hollow cylindrical member and the opening 107 throughout the range of longitudinal movement of the movable member 95. Also, the stroke of the piston 97 in the cylinder 103 is at least equal to the range of longitudinal movement of the member 95 so that the opening 107 and the cylinder 103 function as guides for the member 95. A helical spring 111 is positioned in the chamber 105 between the upper end surface of the piston 97 and the end wall of the cylinder 103 to normally urge the movable member 95 downwardly to the position shown in Fig. 2. A downward force is also applied to the member 95 by the pressure of the fluid in the chamber 105 acting on the piston 97, the fluid being supplied to the chamber through a longitudinal passageway 112 extending throughout the valve stem from the lower side of the plate member 99. The member 95 is moved upwardly to the position shown in Fig. 3 by the pressure of the fluid acting on the lower surface of the plate member 99. In this position of the member 95 the continuous surface portion 102 of the hollow cylindrical member 100 extends upwardly beyond the upper surface of the annular flange member 106 and blocks fluid flow across the annular flange member 106 by way of the openings 101. However, a plurality of restricted orifices 113 located in the plate member 99 radially inwardly of the hollow cylindrical member permits limited fluid flow across the flange member 106 when the member 95 is in the latter position.

The effective area of the piston 97 and the size of the spring 112 are proportioned with respect to the effective area of the plate member 99 so that the member 95 moves to its uppermost, or "closed" position, as shown in Fig. 3, whenever the pressure of the fluid on the regenerator side, or at the inlet of the casing 91 exceeds a predetermined value. In this position, the fluid flows from the inlet to the outlet only through the orifices 113 and any desired predetermined maximum rate of flow may be established by calibration of these orifices. When the pressure of the fluid at the inlet drops to a value such that the downward force presented by the spring 112 and the pressure of the fluid acting on the piston 97 exceeds the upward force presented by the pressure of the fluid acting on the plate member 99, the member 95 begins to move downwardly from its position shown in Fig. 3. Upon sufficient downward movement of the member 95, the lower ends of the openings 101 extend downwardly beyond the lower surface of the annular flange member

106 to allow fluid flow around the periphery of the plate member 99 and through the opening 107. Due to the tapered shape of the openings 101, the effective size of the opening 107 gradually increases as the member 95 moves further downwardly, and maximum opening is attained when the member 95 moves to its lowermost or "open" position, shown in Fig. 2. In the latter position minimum restriction is offered to fluid flow through the casing 91 in either direction.

The flow control valves 90 are operable to automatically limit the rate of fluid flow therethrough to below a predetermined value whenever the regenerator inlet of the casing 91 is subject to a relatively high pressure, such as the relatively high pressure residual fluid existing in the regenerator chamber 83 upon the regenerator being switched when passing a stream of relatively high pressure gaseous mixture. The orifices 113 may be calibrated to maintain the rate of fluid flow through the valve below a predetermined critical value for the maximum inlet pressure as determined by the pressure of the fluid in the chamber 83. Also, the valve is operable to exhaust the relatively high pressure residual fluid in the chamber 83 during the shortest period of time while maintaining the rate of fluid flow through the casing 91 below the predetermined critical value. This is accomplished by the feature of increasing the effective size of the opening 107 responsively to decreases in inlet pressure.

Operation of the flow control valves 90 will be more fully understood by consideration of their performance in the fractionating cycle shown in Fig. 1. Upon the switching devices 27, 28, 37, 38, 46, 47, 55 and 56 being moved to the positions shown, streams of incoming gaseous mixture under relatively high pressure, such as compressed air, flow downwardly through the regenerators 16 and 18, while cold product streams under relatively low pressure, such as nitrogen and oxygen product streams, flow upwardly through the regenerators 17 and 19, respectively. During this phase of operation the flow control valves 90 associated with each regenerator are in their "open" positions, shown in Fig. 2, in which the valves present a minimum restriction to fluid flow therethrough in either direction. The nitrogen and oxygen product streams are introduced into the lower ends of the regenerators 17 and 19 at a pressure substantially corresponding to the pressure of the low pressure section of the fractionating column, which may be in the order of 4 pounds gage, for example. Since the product streams are exhausted from the upper ends of the regenerators at atmospheric pressure, a pressure drop of 3 pounds per square inch will exist across the bed 84 of packing material. In an installation in which the regenerators are packed to a height of 21 feet with heat adsorbing material having a density of 110 pounds per cubic foot, such as quartzite, a lifting force of approximately 20.6 pounds per cubic foot will be exerted on the packing material by the pressure drop resulting from the flow of the cold product streams upwardly through the regenerators. This lifting force is about one fifth the density of the packing material and is insufficient to disturb the bed.

When the switching valves are simultaneously moved to their other phase of operation, the cold product streams are conducted upwardly through the regenerators 16 and 18, while the streams of gaseous mixture are conducted downwardly through the regenerators 17 and 19 previously cooled by the cold product streams. During this phase of operation the flow control valves associated with the regenerators 17 and 19 remain in the "open" position, while the flow control valves connected to the regenerators 16 and 18 move to the "closed" position, as shown in Fig. 3, responsively to the residual volume of relatively high pressure gaseous mixture present in the latter regenerators at the time the switching valves are operated. In the fractionation of air, as mentioned above, the incoming air stream may be under a

5 pressure of 80 pounds gage, in which case the residual volume of air in the regenerator chambers will be at a corresponding pressure. In such case the flow control valves 90 are designed with the effective areas of the disc member 99 and the piston 97 and the size of the spring 112 properly proportioned so that the relatively high pressure residual air moves the member 95 to the position shown in Fig. 3 and maintains the member 95 in closed position until the pressure of the air in the regenerator chamber 83 drops to below a critical value. When the flow control valves associated with the regenerators 16 and 18 are closed, the residual air flows from the respective regenerators through the restricted orifices 113. These orifices are calibrated to establish a maximum permissible rate of flow, at the maximum pressure of the residual air, such that the resulting lifting force on the bed of packing material is less than the density of the packing material. In the case of quartzite packing material of a density of 110 pounds per cubic foot packed to a height of 21 feet in the regenerators, the orifices 113 are calibrated to provide a maximum permissible rate of flow, when subject to a pressure head of 80 pounds gage, to produce a pressure drop across the packing material less than the density of the packing material, or less than five times the pressure drop developed during upward flow of cold product streams through the regenerators. Since the pressure drop varies as the square of the mass flow and inversely as the density, the required orifice size may be easily calculated. In the present example, the orifices 113 are designed to provide a maximum permissible rate of flow less than 5.45 times the rate of flow of the cold product streams.

35 As the residual air exhausts from the regenerator chamber, the pressure of the residual air remaining in the regenerator chamber decreases with a proportional decrease in the flow through the orifices 113. Inasmuch as it is advantageous to exhaust the residual air from the regenerators within the shortest period of time, the flow control valves are characterized in such a manner as to maintain, upon a gradual decrease of the pressure of the residual air in the regenerator chambers, the rate of flow of the residual air therethrough less than, but in the neighborhood of, the maximum permissible rate of flow. This is accomplished by proportioning of the effective areas of the plate member 99 and the piston 97 and the strength of the spring 112 to cause the member 95 gradually to move downwardly from the closed position to the open position responsively to a progressive pressure drop in the regenerator chamber while maintaining the rate of flow below the maximum permissible rate. When the member 95 moves downwardly to a position wherein the closed ends of the openings 111 extend downwardly beyond the lower surface of the annular flange member 106, the effective size of the orifice in the annular flange member 106 is increased and a predetermined rate of flow may be maintained with a reduced pressure head. The rate of downward movement of the member 95, and the shape of the openings 111, are proportioned in accordance with the pressure gradient within the regenerator chamber, to maintain the rate of flow from the regenerator less than the maximum permissible rate of flow discussed above.

65 The flow control valves may be designed to operate responsively to any degree of pressure drop to increase the effective size of the opening 107 presented by the annular flange member 106. The operating requirements of the cycle and the sensitivity of the flow control valves are primary factors in determining the degree of pressure reduction required for this operation. If desired, the variable orifice may be caused to open responsively to a pressure reduction of the order of one pound or less, however such an operation would require a flow control valve of extremely high sensitivity and the resulting relatively minute reduction of the exhaust period may not

ordinarily justify the expense involved. In general, a flow control valve operable to increase the size of the orifice responsive to a regenerator chamber pressure intermediate the maximum residual air pressure and the cold product pressure, or less, may be manufactured at relatively low cost to possess the necessary sensitivity and also provide for the exhaust of the residual air within a period of time which does not adversely effect column operation. For example, in a fractionating cycle in which the air stream is introduced at 80 pounds gage and the cold product streams enter the regenerators at 4 pounds gage, the elements of the flow control valves may be proportioned to initiate downward movement of the member 95 upon the regenerator chamber pressure dropping to 40 pounds gage, and thereafter being operable to progressively increase the size of the orifice responsive to further deduction of the pressure head to exhaust the residual air and establish a regenerator pressure of 4 pounds gage within a period of less than five seconds. This short exhausting period approaches the lower range of interrupted nitrogen flow present during operation of conventional fractionating cycles employing switching tubular heat exchangers or switching regenerators. Consequently, the provision of the flow control valves according to the present invention does not increase the pressure in the low pressure section of the column or reduce the rate of evolution as compared to conventional cycles, but in some cases actually decreases the exhaust period and minimizes their effect.

Another form of flow control valve provided by the present invention is illustrated in Fig. 5 of the drawings. As shown, the valve includes a hollow cylindrical casing 125 having its lower end 126 secured to the upper end plate 81 of a regenerator, such as the regenerator 16, in communication with the regenerator chamber 83, and its upper end 127 provided with an annular flange 128. A hollow cylindrical member 129, having a closed upper end 130, is rigidly supported concentrically within the case 125 by means of a plurality of radial vanes 131, and an elongated valve stem 132 is slidably mounted longitudinally of the casing in a centrally disposed opening 133 formed in the end plate 130. A hollow valve member 134 including cylindrical side walls 135 and upper and lower end plates 136 and 137 respectively, overlies the lower end of the valve stem 132, and is rigidly secured thereto in concentric relation. The cylindrical side walls 135 are shaped so that the upper end of the valve member 134 extends into the hollow cylindrical member 129 in sliding contact with its internal surface upon longitudinal movement of the valve stem 132. The upper end of the valve member 134 and the cylindrical member 129 function as a piston and cylinder assembly and together define a chamber 138. The lower end of the valve member 134 extends through a circular opening 139 formed by an annular flange 140 secured to the casing 125 below the cylindrical member 129. The end plate 137 of the valve member 134 extends outwardly beyond the cylindrical side walls 135 and is positioned below the annular flange 140 to contact the lower surface of the latter flange and limit upward movement of the valve stem 132. The valve stem 132 extends upwardly beyond the closed end 130 of the cylindrical member 129 and is joined to a valve operating member 141 comprising a transversely disposed concentrically positioned circular plate having a diameter less than the internal diameter of the casing 125 to form an annular opening 142 between the peripheral edge of the plate and the adjacent inside surface of the casing. The plate includes a plurality of downwardly depending stop members 143 which function to limit downward movement of the valve operative member and space the plate 141 from the upper surface of the closed end 130 of the cylindrical member 129. The valve stem 132 is provided with a longitudinal passageway 144 extending from its lower end 145 upwardly beyond the end plate 136 of the valve member

where the passageway communicates with the chamber 138 through a port 146. The passageway 144 equalizes the pressures acting on the end plates 136 and 137, and the end plates are proportioned to present equal effective areas so that the valve member moves independently of the inlet pressure. The end plate 137 is provided with a plurality of restricted orifices 147, and the side walls 135 are provided with angularly spaced longitudinally extending openings 148, of varying area, to control the flow of fluid across the annular flange 140.

In operation of the flow control valve shown in Fig. 5, when the inlet is subject to a relatively high pressure, such as high pressure residual air present in the regenerator chamber 83 at the time the regenerator is switched to pass a stream of cold product upwardly therethrough, the high rate of flow through the fixed annular orifice 142 produces a pressure drop across the valve operating member 141 causing the valve operating member and the valve member 134 to move upwardly to its maximum or "closed" position shown in the drawing. In this position fluid flows only through the restricted orifices 147 and these orifices may be calibrated to provide a predetermined maximum permissible rate of flow. As the inlet pressure decreases, the pressure drop across the valve operating member 141 decreases therewith, and a condition is eventually attained in which the upward force on the valve operating member is less than the downward force determined by the mass of the valve member 134 and its connected moving elements. When the latter force relationship exists, the valve member 134 moves downwardly relatively to the annular flange 140 to position the openings 148 below the lower surface of the annular flange 140 and thus increase the size of the opening across the annular flange. Since the valve member moves independently of the pressure of the fluid, the valve member is automatically positioned relative to the annular flange to maintain a constant rate of fluid flow through the casing 125 independently of pressure variations. This form of flow control valve has particular utility in connection with regenerators, although it may be employed in other environments, since substantially the total volume of residual gas may be exhausted from the regenerator chamber at a substantially constant rate of flow no greater than the maximum rate of flow established by the fixed orifices 147.

There is thus provided by the present invention a novel cycle for the separation of gaseous mixtures by liquefaction and fractionation including cold regenerators containing beds of packing material made up of small heat absorbing particles, in which the rate of flow of high pressure residual gaseous mixture from the regenerators is controlled in such a manner as to prevent disturbance of the bed and resulting production of fines due to attrition or crushing of the heat absorbing particles, without increasing substantially the time required to exhaust the residual gaseous mixture. The present invention also provides two forms of flow control valves which may be utilized with regenerator to achieve the foregoing operation. The flow control valves have utility in other environments requiring a controlled rate of fluid flow, and one of the flow control valves is capable of maintaining substantially constant rate of flow independently of pressure.

Although several embodiments of the invention have been disclosed and described above, it is to be expressly understood that various changes and substitutions may be made therein without departure from the spirit of the invention as well understood by those skilled in the art. Reference therefore will be had to the appended claims for a definition of the limits of the invention.

What is claimed is:

1. Method of operating a regenerator including a bed of particles of regenerative material and adapted to be switched between first and second operating phases, in which relatively high pressure fluid flows through the

regenerator during the first operating phase and relatively low pressure fluid flows through the regenerator during the second operating phase, the method of controlling the flow of relatively high pressure fluid in the bed upon switching the regenerator from one operating phase to the other operating phase which comprises the steps of restricting the flow of relatively high pressure fluid in the bed upon the regenerator being switched from one operating phase to the other operating phase to maintain the pressure drop across the bed less than a predetermined value to produce an upward force on the bed less than the density of the regenerative material, and establishing normal unrestricted flow of fluid in the bed upon the pressure of fluid in the bed decreasing to a predetermined low value, the predetermined low value being such that normal unrestricted flow of fluid in the bed at a pressure corresponding to the predetermined low value establishes a pressure drop across the bed which produces an upward force on the bed less than the density of the regenerative material.

2. Method of operating a regenerator including a bed of particles of regenerative material and adapted to be switched between first and second operating phases, in which relatively high pressure fluid flows through the regenerator during the first operating phase and relatively low pressure fluid flows through the regenerator during the second operating phase, the method of controlling the flow of relatively high pressure fluid in the bed upon switching the regenerator from one operating phase to the other operating phase which comprises the steps of restricting the flow of relatively high pressure fluid in the bed upon the regenerator being switched from one operating phase to the other operating phase to maintain the pressure drop across the bed less than a predetermined value to produce an upward force on the bed less than the density of the regenerative material, decreasing the restriction to the flow of relatively high pressure fluid in the bed as the pressure drop across the bed decreases while maintaining the flow of fluid in the bed such that the resulting pressure drop across the bed is less than said predetermined value, and establishing normal unrestricted flow of fluid in the bed upon the pressure of fluid in the bed decreasing to a predetermined low value, the predetermined low value being such that normal unrestricted flow of fluid in the bed at a pressure corresponding to the predetermined low value establishes a pressure drop across the bed which produces an upward force on the bed less than the density of the regenerative material.

3. Method of operating a regenerator including a bed of particles of regenerative material and adapted to be switched between first and second operating phases, in which relatively high pressure fluid flows downwardly through the regenerator during the first operating phase and relatively low pressure fluid flows upwardly through the regenerator during the second operating phase, the method of controlling the flow from the regenerator of relatively high pressure fluid remaining in the regenerator upon the regenerator being switched from the first operating phase to the second operating phase to prevent movement of particles forming the bed and the resulting production of fines, the method comprising the steps of restricting the flow of relatively high pressure fluid from the regenerator upon the regenerator being switched from the first operating phase to the second operating phase to maintain the pressure drop across the bed less than a predetermined value to produce an upward force on the bed less than the density of the regenerative material, and establishing normal unrestricted flow of fluid from the regenerator upon the pressure of fluid in the regenerator decreasing to a predetermined low value, the predetermined low value being such that normal unrestricted flow of fluid in the bed at a pressure corresponding to the predetermined low value establishes a pressure drop across the bed which produces an up-

ward force on the bed less than the density of the regenerative material.

4. Method of operating a regenerator including a bed of particles of regenerative material and adapted to be switched between first and second operating phases, in which relatively high pressure fluid flows downwardly through the regenerator during the first operating phase and relatively low pressure fluid flows upwardly through the regenerator during the second operating phase, the method of controlling flow from the regenerator of relatively high pressure fluid remaining in the regenerator upon the regenerator being switched from the first operating phase to the second operating phase to prevent movement of particles forming the bed and the resulting production of fines, the method comprising the steps of restricting the flow of relatively high pressure fluid from the regenerator upon the regenerator being switched from the first operating phase to the second operating phase to maintain the pressure drop across the bed less than a predetermined value to produce an upward force on the bed less than the density of the regenerative material, decreasing the restriction to the flow of relatively high pressure fluid from the regenerator as the pressure drop across the bed decreases while maintaining the flow of fluid from the regenerator such that the resulting pressure drop across the bed is less than said predetermined value, and establishing normal unrestricted flow of fluid in the bed upon the pressure of fluid in the bed decreasing to a predetermined low value, the predetermined low value being such that normal unrestricted flow of fluid in the bed at a pressure corresponding to the predetermined low value establishes a pressure drop across the bed which produces an upward force on the bed less than the density of the regenerative material.

5. In the separation of gaseous mixtures by a fractionating operation employing a switching regenerator including a bed of particles of regenerative material and adapted to be switched between first and second operating phases, in which relatively high pressure gaseous mixture to be fractionated flows through the regenerator during the first operating phase and relatively low pressure cold product from the fractionating operation flows through the regenerator during the second operating phase, the method of controlling the flow of relatively high pressure gaseous mixture in the bed upon switching the regenerator from one operating phase to the other operating phase to prevent movement of particles forming the bed and the resulting production of fines, the method comprising the steps of restricting the flow of relatively high pressure gaseous mixture in the bed upon the regenerator being switched from one operating phase to the other operating phase to maintain the pressure drop across the bed less than a predetermined value to produce an upward force on the bed less than the density of the regenerative material, and establishing normal unrestricted flow of gaseous mixture in the bed upon the pressure of gaseous mixture in the bed decreasing to a predetermined low value, the predetermined low value being such that normal unrestricted flow of gaseous mixture in the bed at a pressure corresponding to the predetermined low value establishes a pressure drop across the bed which produces an upward force on the bed less than the density of the regenerative material.

6. In the separation of gaseous mixtures by a fractionating operation employing a switching regenerator including a bed of particles of regenerative material and adapted to be switched between first and second operating phases, in which relatively high pressure gaseous mixture to be fractionated flows downwardly through the regenerator during the first operating phase and relatively low pressure cold product from the fractionating operation flows upwardly through the regenerator during the second operating phase, the method of controlling the flow of relatively high pressure gaseous mixture in the

bed upon switching the regenerator from one operating phase to the other operating phase to prevent movement of particles forming the bed and the resulting production of fines, the method comprising the steps of restricting the flow of relatively high pressure gaseous mixture in the bed upon the regenerator being switched from one operating phase to the other operating phase to maintain the pressure drop across the bed less than a predetermined value to produce an upward force on the bed less than the density of the regenerative material, decreasing the restriction to the flow of relatively high pressure gaseous mixture in the bed as the pressure drop across the bed decreases while maintaining the flow of gaseous mixture in the bed such that the resulting pressure drop is less than said predetermined value, and establishing normal unrestricted flow of gaseous mixture in the bed upon the pressure of fluid in the bed decreasing to a predetermined low value, the predetermined low value being such that normal unrestricted flow of gaseous mixture in the bed at a pressure corresponding to the predetermined low value establishes a pressure drop across the bed which produces an upward force on the bed less than the density of the regenerative material.

7. In the separation of gaseous mixtures by a fractionating operation employing a switching regenerator including a bed of particles of regenerative material and adapted to be switched between first and second operating phases, in which relatively high pressure gaseous mixture to be fractionated flows downwardly through the regenerator during the first operating phase and relatively low pressure cold product from the fractionating operation flows upwardly through the regenerator during the second operating phase, the method of controlling flow from the regenerator of gaseous mixture remaining in the regenerator upon the regenerator being switched from the first operating phase to the second operating phase to prevent movement of particles forming the bed and the resulting production of fines, the method comprising the steps of restricting flow of gaseous mixture from the regenerator upon the regenerator being switched from the first operating phase to the second operating phase to maintain the flow of residual gaseous mixture from the regenerator below a maximum flow such that the resulting pressure drop across the bed of regenerative material produces an upward force on the bed which is less than the density of the regenerative material, and establishing normal unrestricted flow of gaseous mixture in the regenerator upon the gaseous mixture in the regenerator dropping to a predetermined low pressure, the predetermined low value being such that normal unrestricted flow of gaseous mixture from the regenerator at the predetermined low pressure establishes a pressure drop across the bed of regenerative material producing an upward force on the bed less than the density of the regenerative material.

8. In the separation of gaseous mixtures by a fractionating operation employing a switching regenerator including a bed of particles of regenerative material and adapted to be switched between first and second operating phases, in which relatively high pressure gaseous mixture to be fractionated flows downwardly through the regenerator during the first operating phase and relatively low pressure cold product from the fractionating operation flows upwardly through the regenerator during the second operating phase, the method of controlling the flow from the regenerator of gaseous mixture remaining in the regenerator upon the regenerator being switched from the first operating phase to the second operating phase to prevent movement of particles forming the bed and the resulting production of fines, the method comprising the steps of restricting the flow of gaseous mixture from the regenerator upon the regenerator being switched from the first operating phase to the second operating phase to establish a maximum flow of

gaseous mixture from the regenerator such that the resulting pressure drop across the bed of regenerative material produces an upward force on the bed which is less than the density of the regenerative material, decreasing the restriction to the flow of gaseous mixture from the regenerator as the pressure of the gaseous mixture in the regenerator decreases while maintaining the flow of gaseous mixture from the regenerator below the maximum flow, and establishing normal unrestricted flow of gaseous mixture from the regenerator upon the gaseous mixture in the regenerator dropping to a predetermined low pressure, the predetermined low pressure being such that normal unrestricted flow of gaseous mixture from the regenerator at the predetermined low pressure establishes a pressure drop across the bed of regenerative material producing an upward force on the bed less than the density of the regenerative material.

9. In the separation of gaseous mixtures by a fractionating operation employing a switching regenerator including a bed of particles of regenerative material and adapted to be switched between first and second operating phases, in which relatively high pressure gaseous mixture to be fractionated flows downwardly through the regenerator during the first operating phase and relatively low pressure cold product from the fractionating operation flows upwardly through the regenerator during the second operating phase, the method of controlling the flow from the regenerator of gaseous mixture remaining in the regenerator upon the regenerator being switched from the first operating phase to the second operating phase to prevent movement of particles forming the bed and the resulting production of fines, the method comprising the steps of restricting the flow of gaseous mixture from the regenerator upon the regenerator being switched from the first operating phase to the second operating phase to establish a maximum flow of residual gaseous mixture from the regenerator such that the resulting pressure drop across the bed of regenerative material produces an upward force on the bed which is less than the density of the regenerative material, progressively decreasing the restriction to the flow of gaseous mixture from the regenerator as the pressure of the gaseous mixture in the regenerator decreases while at all times maintaining the flow of gaseous mixture from the regenerator below the maximum flow, and establishing normal unrestricted flow of gaseous mixture from the regenerator upon the gaseous mixture in the regenerator dropping to a predetermined low pressure, the predetermined low pressure being such that normal unrestricted flow of gaseous mixture from the regenerator at the predetermined low pressure establishes a pressure drop across the bed of regenerative material producing an upward force on the bed less than the density of the regenerative material.

10. In the separation of gaseous mixtures by a fractionating operation employing a switching regenerator including a bed of particles of regenerative material and adapted to be switched between first and second operating phases, in which relatively high pressure gaseous mixture to be fractionated flows downwardly through the regenerator during the first operating phase and relatively low pressure cold product from the fractionating operation flows upwardly through the regenerator during the second operating phase, the method of controlling the flow from the regenerator of gaseous mixture remaining in the regenerator upon the regenerator being switched from the first operating phase to the second operating phase to prevent movement of particles forming the bed and the resulting production of fines, the method comprising the steps of restricting the flow of gaseous mixture from the regenerator upon the regenerator being switched from the first operating phase to the second operating phase to maintain the flow of gaseous mixture from the regenerator below a predetermined maximum flow such that the resulting pressure drop across the bed of regenerative ma-

terial produces an upward force on the bed which is less than the density of the regenerative material, establishing normal unrestricted flow of gaseous mixture from the regenerator upon the gaseous mixture in the regenerator dropping to a predetermined low pressure, the predetermined low pressure of the gaseous mixture being such that normal unrestricted flow from the regenerator of gaseous mixture at the predetermined low pressure establishes a pressure drop across the bed of regenerative material producing an upward force on the bed less than the density of the regenerative material, and establishing normal unrestricted flow of gaseous mixture downwardly through the regenerator upon the regenerator being switched from the second operating phase to the first operating phase.

11. In the separation of gaseous mixtures by a fractionating operation employing switching regenerators each including a bed of particles of regenerative material and adapted to be alternately switched between first and second operating phases, in which gaseous mixture under relatively high pressure flows downwardly through one of the regenerators and relatively low pressure cold product from the fractionating operation flows upwardly through another regenerator during the first operating phase and in which gaseous mixture under relatively high pressure flows downwardly through the another regenerator and relatively low pressure cold product flows upwardly through the one regenerator during the second operating phase, the method of controlling the flow from the regenerators of gaseous mixture under relatively high pressure remaining in the regenerators upon the regenerators being switched to flow relatively low pressure cold product upwardly through the regenerators to prevent movement of particles forming the beds and resulting production of fines, the method comprising the steps of establishing normal flow of gaseous mixture downwardly through one regenerator upon the one regenerator being switched from the second operating phase to the first operating phase, restricting the flow of gaseous mixture from another regenerator upon the another regenerator being switched from the first operating phase to the second operating phase to establish a predetermined maximum flow of gaseous mixture from the another regenerator with a resulting pressure drop across the bed of regenerative material producing an upward force on the bed less than the density of the regenerative material, establishing normal unrestricted flow of gaseous mixture from the another regenerator upon the gaseous mixture in the another regenerator dropping to a predetermined low pressure, the predetermined low pressure of the gaseous mixture being such that normal unrestricted flow of gaseous mixture from the another regenerator at the predetermined low pressure establishes a pressure drop across the bed of regenerative material producing an upward force on the bed less than the density of the regenerative material.

12. In the separation of gaseous mixtures by fractionating operation employing switching regenerators each including a bed of particles of regenerative material and adapted to be alternately switched between first and second operating phases, in which gaseous mixture under relatively high pressure flows downwardly through one of the regenerators and relatively low pressure cold product from the fractionating operation flows upwardly through another regenerator during the first operating phase and in which gaseous mixture under relatively high pressure flows downwardly through the another regenerator and relatively low pressure cold product flows upwardly through the one regenerator during the second operating phase, the method of controlling the flow from the regenerators of gaseous mixture under relatively high pressure remaining in the regenerators upon the regenerators being switched to flow relatively low pressure cold product upwardly through the regenerators to prevent movement of particles forming the beds and resulting production of

fines, the method comprising the steps of establishing normal flow of gaseous mixture downwardly through one regenerator upon the one regenerator being switched from the second operating phase to the first operating phase, restricting the flow of gaseous mixture from another regenerator upon the another regenerator being switched from the first operating phase to the second operating phase to establish a predetermined maximum flow of gaseous mixture from the another regenerator such that the resulting pressure drop across the bed of regenerative material produces an upward force on the bed of regenerative material less than the density of the regenerative material, maintaining normal flow of gaseous mixture downwardly through the one regenerator and progressively reducing the restricted flow of gaseous mixture from the another regenerator as the pressure of the gaseous mixture in the another regenerator decreases while maintaining the flow of gaseous mixture from the another regenerator below the predetermined maximum flow until the pressure of gaseous mixture in the another regenerator drops to a relatively low predetermined value such that the resulting pressure drop produced across the bed upon unrestricted flow of gaseous mixture from the another regenerator at the relatively low value produces an upward force on the bed less than the density of the regenerative material, and providing unrestricted normal flow of gaseous mixture from the another regenerator upon the pressure of the gaseous mixture in the another regenerator dropping to the relatively low value.

13. In the separation of gaseous mixtures by a fractionating operation employing switching regenerators each including a bed of particles of regenerative material and adapted to be alternately switched between first and second operating phases, in which gaseous mixture under relatively high pressure flows downwardly through one of the regenerators and relatively low pressure cold product from the fractionating operation flows upwardly through another regenerator during the first operating phase and in which gaseous mixture under relatively high pressure flows downwardly through the another regenerator and relatively low pressure cold product flows upwardly through the one regenerator during the second operating phase, the method of controlling the flow from the regenerators of gaseous mixture under relatively high pressure remaining in the regenerators upon the regenerators being switched to flow relatively low pressure cold product upwardly through the regenerators to prevent movement of particles forming the beds and the resulting production of fines, the method comprising the steps of establishing normal flow of gaseous mixture downwardly through one regenerator upon the one regenerator being switched from the second operating phase to the first operating phase, restricting the flow of gaseous mixture from another regenerator upon the another regenerator being switched from the first operating phase to the second operating phase to establish a predetermined maximum flow of gaseous mixture from the another regenerator such that the resulting pressure drop across the bed of regenerative material produces an upward force on the bed less than the density of the regenerative material, maintaining normal flow of gaseous mixture downwardly through the one regenerator while progressively reducing the restriction to flow of gaseous mixture from the another regenerator as the pressure of gaseous mixture in the another regenerator decreases to maintain flow of gaseous mixture from the another regenerator below the predetermined maximum flow until the pressure of gaseous mixture in the another regenerator drops to a predetermined low value such that the pressure drop produced across the bed upon unrestricted flow of gaseous mixture from the another regenerator at the relatively low value produces an upward force on the bed less than the density of the regenerative material, providing unrestricted normal flow of gaseous mixture from the another regenerator upon the pressure of the gaseous

mixture in the another regenerator dropping to a relatively low value, and establishing normal flow of gaseous mixture downwardly through the another regenerator upon the another regenerator being switched from the second operating phase to the first operating phase, and establishing restricted flow of gaseous mixture from the one regenerator upon the one regenerator being switched from the first operating phase to the second operating phase, and controlling the restricted flow of gaseous mixture from the one regenerator to maintain the flow of gaseous mixture from the one regenerator below the predetermined maximum flow until the pressure of the gaseous mixture in the one regenerator drops to the relatively low value and thereafter establishing unrestricted normal flow of gaseous mixture from the one regenerator.

14. In combination with a regenerator comprising a bed of particles of regenerative material and means including conduit means and switching means for alternately flowing fluids under different pressures through the bed, valve means in the conduit means for controlling the flow of fluid through the bed upon operation of the switching means to terminate the flow through the regenerator of fluid under one pressure and initiate the flow through the regenerator of fluid under a different pressure, the valve means including means operable responsively to a pressure differential between fluid in the regenerator and fluid in the conduit means for restricting to a predetermined value the flow of fluid in the bed such that the pressure drop developed across the bed produces an upward force on the bed less than the density of the regenerative material.

15. In combination with a regenerator comprising a bed of particles of regenerative material and means including conduit means and switching means for flowing high pressure fluid downwardly through the regenerator when switched to one operating phase and for flowing relatively low pressure fluid upwardly through the regenerator when switched to another operating phase, valve means in the conduit means for controlling the flow of high pressure fluid in the regenerator upon operation of the switching means to terminate the flow through the regenerator of high pressure fluid and initiate the flow through the regenerator of relatively low pressure fluid, the valve means including means operable responsively to the relatively high pressure of the fluid in the regenerator for restricting to a predetermined value the flow of high pressure fluid from the regenerator such that the pressure drop developed across the bed of regenerative material produces an upward force on the bed less than the density of the regenerative material, and means for establishing normal unrestricted flow from the regenerator upon the pressure of the fluid in the regenerator dropping to a value such that the resulting pressure drop across the bed produces an upward force on the bed less than the density of the regenerative material.

16. In combination with a regenerator comprising a bed of particles of regenerative material and means including conduit means and switching means for alternately flowing fluids under different pressure through the bed, valve means in the conduit means for controlling the flow of fluid in the bed upon operation of the switching means to terminate the flow through the regenerator of fluid under one pressure and initiate the flow through the regenerator of fluid under a different pressure, the valve means including means operable responsively to a pressure differential between fluid in the regenerator and fluid in the conduit means for restricting to a predetermined value the flow of fluid in the bed such that the resulting pressure drop across the bed produces an upward force on the bed less than the density of the regenerative material, means for progressively increasing

the flow of fluid in the bed as the pressure of the fluid in the bed decreases, and means for establishing normal unrestricted flow in the bed upon the pressure differential dropping to a value such that the resulting pressure drop across the bed produces an upward force on the bed less than the density of the regenerative material.

17. In combination with a regenerator comprising a bed of particles of regenerative material and means including conduit means and switching means for flowing fluid under relatively high pressure downwardly through the bed when the switching means is moved to one phase and for flowing fluid under relatively low pressure upwardly through the bed when the switching means is moved to a second phase, valve means including means operable responsively to fluid under relatively high pressure in the regenerator upon the regenerator being switched to the first phase to restrict to a predetermined value the flow of fluid from the bed such that the pressure drop developed across the bed produces an upward force on the bed less than the density of the regenerative material, means for progressively increasing the flow of fluid from the regenerator as the pressure of the fluid in the regenerator decreases, and means for establishing normal unrestricted flow from the regenerator upon the pressure differential dropping to a value such that the pressure drop developed across the bed produces an upward force on the bed less than the density of the regenerative material.

18. In the separation of gaseous mixtures by a fractionating operation employing a switching regenerator including a bed of particles of regenerative material and adapted to be switched between first and second operating phases, in which relatively high pressure gaseous mixture to be fractionated flows downwardly through the regenerator during the first operating stage and relatively low pressure product from the fractionating operation flows upwardly through the regenerator during the second operating stage, valvular means for controlling flow from the regenerator of gaseous mixture remaining in the regenerator upon the regenerator being switched from the first operating phase to the second operating phase to prevent movement of particles forming the bed and the resulting production of fines, the valvular means including means for restricting the flow of gaseous mixture from the first operating phase to the second operating phase to maintain the flow of gaseous mixture from the regenerator below a predetermined maximum flow such that the resulting pressure drop across the bed of regenerative material produces an upward force on the bed less than the density of the regenerative material, and means for establishing normal unrestricted flow of gaseous mixture from the regenerator upon the gaseous mixture dropping to a predetermined low pressure, the predetermined low pressure of the gaseous mixture being such that normal unrestricted flow from the regenerator of gaseous mixture at the predetermined low pressure establishes a pressure drop across the bed of regenerative material producing an upward force on the bed less than the density of the regenerative material.

19. In the separation of gaseous mixtures by a fractionating operation employing a switching regenerator including a bed of particles of regenerative material and adapted to be switched between first and second operating phases, in which relatively high pressure gaseous mixture to be fractionated flows downwardly through the regenerator during the first operating phase and relatively low pressure product from the fractionating operation flows upwardly through the regenerator during the second operating phase, valvular means for controlling flow from the regenerator of gaseous mixture remaining in the regenerator upon the regenerator being switched from the first operating phase to the second operating phase to prevent movement of particles forming the bed and the resulting production of fines, said valvular means com-

prising means for restricting the flow of gaseous mixture from the regenerator upon the regenerator being switched from the first operating phase to the second operating phase to establish a predetermined maximum flow of gaseous mixture at the relatively high pressure with the resulting pressure drop across the bed producing an upward force on the bed which is less than the density of the regenerative material, means for progressively decreasing the restriction to the flow of gaseous mixture from the regenerator as the pressure of the gaseous mixture in the regenerator decreases while maintaining the flow of gaseous mixture from the regenerator below the predetermined maximum flow, and means establishing normal unrestricted flow of gaseous mixture from the regenerator upon the gaseous mixture in the regenerator dropping to a predetermined low pressure, the predetermined low pressure being such that normal unrestricted flow of gaseous mixture at the predetermined low pressure from the regenerator establishes a pressure drop across the bed of regenerative material which produces an upward force on the bed less than the density of the regenerative material.

20. In the separation of gaseous mixtures by a fractionating operation employing switching regenerators each including a bed of particles of regenerative material and adapted to be alternately switched between first and second operating phases, in which gaseous mixture under relatively high pressure to be fractionated flows downwardly through one of the regenerators and relatively low pressure cold product from the fractionating operation flows upwardly through another regenerator during the first operating phase and wherein relatively high pressure gaseous mixture flows downwardly through the another regenerator and relatively low pressure cold product flows upwardly through the one regenerator during the second operating phase, valvular means for controlling the flow from the regenerators of gaseous mixture under relatively high pressure remaining in the regenerators upon the regenerators being switched to flow relatively low pressure cold product upwardly through the regenerators to prevent movement of particles forming the bed and resulting production of fines, said valvular means comprising means for establishing normal flow of gaseous mixture downwardly through one regenerator upon the one regenerator being switched from the second operating phase to the first operating phase, means for restricting the flow of gaseous mixture from another regenerator being switched from the first operating phase to the second operating phase, the restricted flow of gaseous mixture establishing a predetermined maximum flow of gaseous mixture from the another regenerator such that the resulting pressure drop developed across the bed of regenerative material produces a lifting force on the bed less than the density of the regenerative material, means for maintaining normal flow of gaseous mixture downwardly through the one regenerator, means for progressively reducing the restriction to flow of gaseous mixture from the another regenerator as the pressure of the gaseous mixture in the another regenerator decreases to maintain the flow of gaseous mixture from the another regenerator below the predetermined maximum flow until the pressure of gaseous mixture in the another regenerator drops to a relatively low value such that the pressure drop developed

across the bed upon unrestricted flow of gaseous mixture from the another regenerator at the relatively low value produces an upward force on the bed less than the density of the regenerative material, means providing unrestricted normal flow of gaseous mixture from the another regenerator when the pressure of the gaseous mixture drops to the relatively low value, means establishing normal flow of gaseous mixture downwardly through the another regenerator upon the another regenerator being switched from the second operating phase to the first operating phase, means for establishing a restricted flow of gaseous mixture from the one regenerator upon the one regenerator being switched from the first operating phase to the second operating phase, and means for controlling the restricted flow of gaseous mixture from the one regenerator to maintain the flow of gaseous mixture from the one regenerator below the predetermined maximum flow until the pressure of the gaseous mixture drops to the relatively low value and thereafter establish unrestricted normal flow of residual gaseous mixture from the one regenerator.

21. In the separation of gaseous mixtures by a fractionating operation employing a regenerator including a bed of particles of regenerative material and adapted to be switched between first and second operating phases, in which gaseous mixture under relatively high pressure flows downwardly through the regenerator during the first operating phase and relatively low pressure cold product from the fractionating operation flows upwardly through the regenerator during the second operating phase, a fluid control valve connected to the regenerator and comprising a casing having an inlet and an outlet, means for forming an opening of variable cross-section between the inlet and the outlet, the last-named means including a valve member mounted for movement to a first position in which a restricted opening is established between the inlet and the outlet and a second position in which a relatively unrestricted opening is established between the inlet and the outlet and to positions intermediate the first and second positions, means operable to progressively increase the size of the opening upon movement of the valve member from the first position to the second position, means for normally urging the valve member to the second position, means operable responsive to a predetermined pressure of fluid at the inlet for moving the valve member to the first position, and means for moving the valve member from the first position in a direction towards the second position in proportion to a drop in pressure of the fluid at the inlet below the predetermined pressure to establish a controlled flow through the opening.
